UNITED STATES PATENT OFFICE

ALPHONSE T. CASSIERE, OF LONG BEACH, CALIFORNIA

FEED WHEEL FOR PNEUMATIC CONCRETE MACHINES

Application filed April 21, 1928. Serial No. 271,696.

An object of my invention is to provide a feed wheel for pneumatic concrete machines in which an accurate amount of material is positively fed into the pressure line each time 5 a space in the feed wheel registers with the outlet.

Another object is to provide a feed wheel in which material can settle and become packed and in which moisture is not deposited 10 in the teeth of the wheel.

A further object is to provide a feed wheel which does not require frequent cleaning or adjustment.

A still further object is to provide a feed 15 wheel in which a steady, even flow of material is emitted into the feed line.

Other objects, advantages, and features of invention may appear from the accompanying drawing, the subjoined, detailed description, 20 and the appended claims.

In the drawing:

Fig. 1 is a fragmentary transverse sectional view of the cement machine with my mixing wheel in position therein.

Fig. 2 is a view similar to Figure 1 but showing a slightly modified type of feed wheel.

Fig. 3 is a plan view of the feed wheel shown in Figure 1.

Referring more particularly to the drawing:

The numeral 1 indicates the main housing of the pneumatic concrete machine, which housing contains the cement which is to be fed through the outlet opening 2 extending from the housing 1. A wall 3 closes the bottom of the housing 1 and a second wall 4, spaced below the wall 3, provides an air chamber 5, the purpose of which will be further described. An air pipe 6 extends through the wall 4, whereby air under pressure is fed into the chamber 5.

A shaft 7 extends into the housing 1 through a stuffing box 8 and the shaft is rotated from a suitable source of power, not shown. A conical feed wheel 9 is secured to the upper end of the shaft 7 and a plurality of radially extending fingers 10 project from the periphery of the wheel 9. The object of 50 these fingers is to entrap a quantity of ce-

ment and as these fingers move past the outlet 2 a blast of air serves to blow the material from between adjacent fingers and out of the outlet 2.

In the form shown in Figure 1, downwardly inclined openings 11 are provided in the wheel 9, said openings communicating with the spaces between adjacent fingers 10. Directly opposite the outlet 2 I provide a nozzle 12 which nozzle extends through the wall 3 and communicates with the chamber 5. Thus, air under pressure is fed through the nozzle 12 and is transmitted through the downwardly inclined ports 11 to eject the material between the fingers 10 and out of the opening 2. A plate 13 is secured to the housing 1 and is positioned over the fingers 10 at the point where they are alined with the outlet 2 so that no material is fed between the fingers at the time that the material is being ejected therefrom.

In the form of my invention shown in Figure 2, ports 14 are provided in the wheel 9^a between adjacent fingers 10, and an annular ring 15 is provided within the wheel 9^a and back of the fingers 10. The ring 15 is stationary and is either integral or is secured to the wall 3. An inlet port 16 is provided in the wall 3 so that air is admitted under the wheel 9^a. At a point opposite the outlet 2 a downwardly inclined port 17 is provided in the ring 15 and as the fingers are alined with the opening 2, the air passing through the port 17 serves to eject the material between the fingers.

To prevent the material from falling between the teeth at the point opposite the outlet 2, the wall of the housing 1 may be extended over the teeth, as shown at 18. To prevent the material from caking in the constricted area above the wheel 9, I provide a plurality of ribs 19 on the upper surface of the wheel.

Having described my invention, I claim:

1. In a pneumatic concrete machine, a hollow feed wheel, a plurality of fingers extending from said wheel, an outlet pipe in the machine with which said fingers are adapted to register, said wheel having openings therein between adjacent pairs of fingers, and means to conduct air under pressure into said feed

wheel and back of said fingers, whereby material between said fingers is ejected through the outlet pipe.

2. In a pneumatic concrete machine comprising a housing, a hollow conical feed wheel in said housing, a plurality of fingers extending from the periphery of the feed wheel, means to rotate the feed wheel, ribs on the outer surface of the feed wheel, an outlet pipe extending from the housing, said fingers being adapted to aline with the outlet pipe, said feed wheel having openings therein communicating with the space between adjacent fingers, and means to conduct air under pressure under the feed wheel back of said openings to eject the material between the fingers through the outlet pipe.

3. In a pneumatic concrete machine comprising a housing, a conical feed wheel in said housing, a plurality of fingers extending from the periphery of the feed wheel, means to rotate the feed wheel, an outlet pipe extending from the housing, said fingers being adapted to aline with the outlet pipe, said feed wheel having openings therein communicating with the space between adjacent fingers, and means to conduct air under pressure back of said openings to eject the material between the fingers, through the outlet pipe, and a stop plate above the fingers adjacent the outlet pipe, and ribs on the surface of the feed wheel.

4. In a pneumatic concrete machine including a housing, a conical feed wheel mounted within the housing, means to rotate said feed wheel, fingers extending radially from the periphery of the feed wheel, an outlet pipe in the housing with which said fingers are adapted to aline, said feed wheel having ports therein communicating with the space between adjacent pairs of fingers, said housing having an air chamber therein below the feed wheel, and a port extending from said chamber under the feed wheel, whereby air under pressure is expelled through the ports and out of the outlet pipe to eject the material between the fingers.

5. In a pneumatic concrete machine including a housing, an outlet pipe extending therefrom, a hollow conical feed wheel in the housing, means to rotate said feed wheel, fingers extending from the periphery of the feed wheel, downwardly inclined ports in the feed wheel communicating with the space between adjacent pairs of fingers, and means to conduct air under pressure under the feed wheel whereby air is passed through the inclined ports to eject the material out of the outlet pipe between the adjacent pairs of fingers.

6. In a pneumatic concrete machine including a housing, an outlet pipe extending therefrom, a hollow conical feed wheel in the housing, means to rotate said feed wheel, fingers extending from the periphery of the feed

wheel, downwardly inclined ports in the feed wheel communicating with the space between adjacent pairs of fingers, said housing having an air chamber formed therein, an air pressure pipe leading to the chamber, and a nozzle extending from said chamber, said nozzle being in alinement with the outlet pipe and adapted to direct air through the inclined ports to eject the material from the outlet pipe.

7. In a pneumatic concrete machine including a housing, an outlet pipe extending therefrom, a hollow conical feed wheel in the housing, means to rotate said feed wheel, fingers extending from the periphery of the feed wheel, downwardly inclined ports in the feed wheel communicating with the space between adjacent pairs of fingers, and means to conduct air under pressure under the feed wheel whereby air is passed through the inclined ports to eject the material out of the outlet pipe between the adjacent pairs of fingers, and stop means above the fingers adjacent the outlet pipe to prevent the passage of material between the fingers as the material is being ejected.

8. In a pneumatic concrete machine including a housing, an outlet pipe extending therefrom, a hollow conical feed wheel in the housing, means to rotate said feed wheel, fingers extending from the periphery of the feed wheel, downwardly inclined ports in the feed wheel communicating with the space between adjacent pairs of fingers, and means to conduct air under pressure under the feed wheel whereby air is passed through the inclined ports to eject the material out of the outlet pipe between the adjacent pairs of fingers, and stop means above the fingers adjacent the outlet pipe to prevent the passage of material between the fingers as the material is being ejected, and ribs formed on the upper surface of the feed wheel.

9. In a pneumatic concrete machine including a housing, an outlet pipe extending therefrom, a hollow conical feed wheel in the housing, means to rotate said feed wheel, fingers extending from the periphery of the feed wheel, downwardly inclined ports in the feed wheel communicating with the space between adjacent pairs of fingers, said housing having an air chamber formed therein, an air pressure pipe leading to the chamber, and a nozzle extending from said chamber, said nozzle being in alinement with the outlet pipe and adapted to direct air through the inclined ports to eject the material from the outlet pipe, and stop means above the fingers adjacent the outlet pipe to prevent the passage of material between the fingers as the material is being ejected, and ribs formed on the upper surface of the feed wheel.

In testimony whereof, I affix my signature.

ALPHONSE T. CASSIERE.
